United States Patent Office.

DAVID M. CUMINGS, OF NEWBURYPORT, MASSACHUSETTS.

Letters Patent No. 104,935, dated July 5, 1870.

IMPROVEMENT IN BUNGS.

The Schedule referred to in these Letters Patent and making part of the same.

To all whom it may concern:

Be it known that I, DAVID M. CUMINGS, of Newburyport, in the county of Essex and State of Massachusetts, have invented a new and useful Improvement in Bungs; and I do hereby declare that the following is a full, clear, and exact description thereof, which will enable others skilled in the art to make and use the same, reference being had to the accompanying drawing forming part of this specification.

This invention relates to improvements in bungs for beer and other casks, and consists in an arrangement for clamping the cover down upon a ring of packing placed on a flange at the bottom of a bush; by a cam-lever having journals let into grooves in the side walls of the bush.

Figure 1 is a sectional elevation of my improved bung.

Figure 2 is a plan view of the same; and

Figure 3 is a view of a hook used for raising the cam-lever.

Similar letters of reference indicate corresponding parts.

A is the bush, screwed into the hole in the stave in the usual way. It is provided with a horizontal flange, B, near the bottom, and with two angular slots, C, in the wall of the hole through it, one opposite the other.

D is a ring of packing substance placed on the flange B; and

E is the cover to be forced down upon it.

F is a cam or cranked lever provided with journals, G,

which drop into the slots C, and turn under the walls over the horizontal parts of the said slots, and hold the lever against moving upward when it is turned down to the position shown in fig. 1, to confine the cap upon the packing.

The lever is held in this position by the upward pressure of the packing on the part H, which, having passed the vertical line, cannot be drawn back without first forcing the packing down again to some extent.

For releasing the cover, the long arm of the cam is raised by pulling it upward with a hook, I, or other suitable device. When it is raised off the cover it is taken out of the slots to admit of the removal of the cover.

The cover E is provided with a flange, R, projecting downward inside of the edge of the flange B, to confine the packing on the said flange, and prevent it from bulging over the edge.

Having thus described my invention,

I claim as new and desire to secure by Letters Patent—

The combination of the bush A, having the flange B, with packing D, cover E, and cam or cranked lever F, when the said lever is fitted in the angular slots C in the wall of the bush, all substantially as specified.

The above specification of my invention signed by me this 2d day of May, 1870.

DAVID M. CUMINGS.
